UNITED STATES PATENT OFFICE.

HENRY L. HAUPT, OF BUTTE, MONTANA.

DESIGN FOR A CALL-BOX AND BASE.

SPECIFICATION forming part of Design No. 30,053, dated January 24, 1899.

Application filed December 14, 1898. Serial No. 699,284. Term of patent 7 years.

To all whom it may concern:

Be it known that I, HENRY L. HAUPT, a citizen of the United States, residing at Butte, in the county of Silver Bow and State of Montana, have invented and produced a certain new and original Design for a Call-Box and Base Therefor; and I do declare the following to be a full, clear, and exact description of the invention, such as will enable others skilled 5 in the art to which it appertains to make and use the same.

The invention relates to a new and original design for a call-box and base therefor; and it consists in a design of the configuration and 15 ornamentation shown in the accompanying drawings, in which—

Figure 1 is a front view of the design. Fig. 2 is a rear view, and Fig. 3 is a longitudinal sectional view.

20 The leading features of my design comprise

a circular base 1, having a rounded edge 2, the curved lines 3, and straight lines 4, the former denoting the lines of latitude and the latter the lines of longitude, the cross-panel 5 of different color from the base of the board, a 25 box-like structure 6, arranged above the panel, the circular dial 7, having a radiating arm on its face, and the grooves 9 and 10 on the rear side of the base intersecting at the axis of the base. 30

What I claim is—

The design for a call-box and base therefor, as herein shown and described.

In testimony whereof I have hereunto set my hand in presence of two subscribing witnesses. 35

HENRY L. HAUPT.

Witnesses:

W. C. BACHELER,

ERNEST A. HARDCASTLE.
